F. L. FULLER,
CAN TOP GUIDING AND EJECTING MECHANISM,
APPLICATION FILED JULY 2, 1913.

Patented May 4, 1915.

UNITED STATES PATENT OFFICE.

FRED LEO FULLER, OF SACRAMENTO, CALIFORNIA.

CAN-TOP GUIDING AND EJECTING MECHANISM.

1,137,750.

Specification of Letters Patent.

Patented May 4, 1915.

Application filed July 2, 1913. Serial No. 777,115.

To all whom it may concern:

Be it known that I, FRED LEO FULLER, a citizen of the United States, residing at Sacramento, in the county of Sacramento and State of California, have invented new and useful Improvements in Can-Top Guiding and Ejecting Mechanisms, of which the following is a specification.

My invention relates to guides for can tops of can capping and seaming machines and the ejection of the finished can. In the adaptation of my improvements, the same has been illustrated in connection with that type of can capping and seaming machines as shown in U. S. Letters Patent No. 1,055,467, wherein the filled cans are automatically fed from the can-top feeding station to the seaming station and wherein provision must be made, when handling cans containing fruit, etc., which protrude above the top of the can, to prevent the top from becoming displaced or tilted until such time as the top is in position to be seamed onto the can. While I have referred to the above U. S. patent, it is to be understood that my invention is not necessarily limited to that particular machine but may be applied to other types as well.

One of the objects of the present invention is to provide a guide for the can top between the time it leaves the cover-guide used in connection with a revolving turret and the time the can top shall be carried to its proper position under the seaming chuck. Difficulty has heretofore been experienced in canning "high" goods, *i. e.*, fruit, fish, vegetables, etc., which stand up above the top of the can before the top is put on, the material to be canned causing the top to be tilted or misplaced and preventing thereby proper seaming. The device which is herewith described is intended to overcome this difficulty and at the same time to act as a stripper for the finished can. With this device it is impossible to puncture the top of the can as is oftentimes the case with ejector rods as heretofore constructed.

I attain these and other incidental objects by the mechanism illustrated in the accompanying drawings forming part of this specification, in which—

Figure 1 is a sectional view through the drive shaft and double seam head of a single spindle flanger; Fig. 2 is a sectional view

through the double seaming head and turret; Fig. 3 is an enlarged view of the upper part of my improved device to show the same more clearly; Fig. 4 is a view in elevation of same, and Fig. 5 is a diagrammatic view illustrating the adaptation of my device and showing "high" fruit in the can.

Similar letters and figures refer to similar parts throughout the several views.

1 is a rod, the lower end of which is provided with a can top guide or plate 2, said rod extending through the hollow chuck-spindle 3. The lever 4 is pivoted on the fixed frame of the machine and is actuated at its inner end by a cam (not shown) see U. S. patent previously referred to, and rod 70 R within the column C, the outer end of the lever being preferably forked and provided with studs 5. On the rod 1 is a collar 6 with set-screw 7 for securing same in fixed position, and above this is a sliding cross-bar 8 mounted on the rod and having studs 9. The forked ends of the lever 4 and the cross-bar 8 are connected by a pair of links 10. Between the fixed collar 6 and the sliding cross-bar 8 is a sliding bushing 11 a little 80 shorter than the distance between the collar and the cross-bar. Surrounding this is a spring 12 under compression bearing against the collar and the cross-bar. Also on the rod 1 and below the fixed collar 6 is another 85 bushing 13 which rests upon the chuck-spindle jam-screw 14 in the column head of the machine; this bushing 13 limits the drop of the rod 1 and consequently fixes, in connection with the collar 6, the lowest position 90 of the guide plate 2.

The operation of the device described is as follows:—The position of the guide plate 2 is normally as shown in Fig. 2. When a can top 15 (see Fig. 5) is about to leave the 95 cover-guard 16 over the turret 17 the outer edge of the top 15 will come under the guide plate 2 before the top has been entirely withdrawn from under the cover-guard; should there be any "high" fruit or other high 100 standing substance in the can, the top will not be displaced or tilted when the can rises for the reason that the top remains practically in the same plane as when leaving the cover-guard and is still retained in 105 the can-top recess on the turret.

The can top having arrived at its proper position, the can is raised by the elevating

mechanism (not shown) which causes the can to bear up against the can top and all to be lifted into position against the chuck 18 ready to be seamed, the plate 2 being forced up into the recess provided for same in the chuck. While the plate 2 is being lifted, the fixed collar 6 on the rod 1 is also lifted causing the bushing 11 to be brought closer to the cross-bar 8, but not changing the relative position of the other parts. When the can top and can have been seamed and the operation has so far advanced that the can is to be ejected, the lever 4 is acted upon by a cam (not shown) and rod R 15 within the column C of the machine, forcing the cross-bar 8 which is attached to the ends of the lever by the links 10, down against the bushing 11 which, bearing against the fixed collar 6, causes the rod 1 and guide plate 2 to be given a slight downward unyielding movement sufficient to release the can from the chuck. As the spring 12 is under compression it will carry the plate 2 still farther down until stopped by the collar 6 coming in contact with the bushing 13 resting on the column-head. The plate 2 is then in position to guide the succeeding can top.

Having thus described my invention,

what I claim as new and desire by Letters 30 Patent to secure, is—

In a can capping apparatus of the class described wherein the cans are automatically fed from the can-top feeding station to the seaming station by means of a revolving 35 turret, and wherein the can bodies with their caps thereon are acted upon by a stationary cover-guide, in combination with a hollow spindle having a recessed seaming chuck on the lower end thereof, a rod 40 extending through said hollow spindle and protruding below said chuck, a guide-plate on the lower end of said rod normally in the same horizontal plane as the stationary cover-guide first mentioned above, a 45 fixed collar on the rod above the hollow spindle, a sliding cross-head on the rod above the fixed collar, a compression spring between said fixed collar and said sliding cross-head, an operating lever pivoted to the 50 main frame of the machine, and links connecting said sliding cross-head to said lever at its extremity.

FRED LEO FULLER.
